UNITED STATES PATENT OFFICE.

JOHN F. SMILEY, OF DALLAS, TEXAS.

SELF-SERVING STORE.

Application filed November 2, 1921. Serial No. 512,338.

To all whom it may concern:

Be it known that I, JOHN F. SMILEY, a citizen of the United States, residing at Dallas, in the county of Dallas and State of Texas, have invented certain new and useful Improvements in Self-Serving Stores; and I do declare the following to be a full, clear, and exact description of the invention, such as will enable others skilled in the art to which it appertains to make and use the same.

This invention relates to a self-serving store in which the customers obtain a basket from a basket bin and after walking about the store and placing different articles desired in the basket, will pass the cashier's counter where the goods purchased will be placed in a bag or other receptacle in which they are to be carried from the store, the cashier attending to placing the goods in the bag and taking payment for the articles purchased.

One object of the invention is to provide a store of the self-serving type in which the articles to be sold will be placed upon shelving against the walls of the store, this store having a certain portion of the shelving forming a partition dividing the rear portion of the store from the main portion thereof and this partition-forming portion of the shelving being so shaped that a maximum amount of shelving may be provided without causing the main portion of the store to be overcrowded by customers and at the same time permitting the clerk at the cashier's counter to have full view of the entire store and petty stealing by customers prevented.

Another object of the invention is to so construct the shelving that the portions forming the partition may have certain sections thereof ingeniously mounted to provide doors which will permit stock clerks to enter the main room and move trucks from the store room into the sales room so that fresh supplies of articles may be placed upon the shelves.

Another object of the invention is to so construct this shelving that it extends continuously from the entrance to the cashier's

desk, the shelving however being formed in sections which are held in close contact with each other by brackets which serve to support a track provided in front of the shelving.

55

Another object of the invention is to provide a self-serving store in which the baskets to hold the articles desired by the purchaser may be placed upon a continuous track provided in front of the shelving and these baskets moved easily along the track and left suspended upon the track while the purchaser is examining various goods and placing desired ones in the basket.

60

Another object of the invention is to provide a roller carrier which may be connected with the handle of the basket and will be so constructed that the basket may be lifted from the track by means of this roller carrier when desired.

65

Another object of the invention is to provide a door of this character in which a card holding frame may be provided along the top of the shelving thus permitting advertising cards to be placed on display, these cards not only attracting the attention of the customers to certain brands of goods handled, but further providing a source of revenue through renting of these advertising spaces.

70

Another object of the invention is to provide a self-serving store in which the arrangement of shelving will provide a larger amount of space for goods to be sold and at the same time provide a store in which the main room will be large and provide space for a larger number of customers without overcrowding.

75

Another object of the invention is to provide a construction of self-serving store in which confusion caused by persons entering and leaving the store will be reduced to a minimum and in which the bins for holding the baskets may form a partition dividing the entrance to the show room from the exit and thus permit of the baskets being easily obtained by a person about to enter the show room and at the same time permits of a customer readily placing an empty basket in the bin.

100

This improved store construction is illustrated in the accompanying drawings, wherein:

Figure 1 is a perspective view of a store 5 provided with the improved construction.

Figure 2 is a top plan view of the improved store construction.

Figure 3 is a fragmentary top plan view 10 of the store.

Figure 4 is a perspective view of two of the shelving units.

Figure 5 is a vertical sectional view 15 through a portion of the shelving, the view being taken along the line 5-5 of Fig. 2.

Figure 6 is a perspective view of sign board units for carrying the advertising cards.

Figure 7 is a sectional view taken along the line 7-7 of Fig. 2.

Figure 8 is a similar view taken along the line 8-8 of Fig. 4.

Figure 9 is a perspective view of a portion of the basket track.

Figure 10 is a sectional view taken along 20 the line 10-10 of Fig. 9.

Figure 11 is a fragmentary transverse sectional view taken along the line 11-11 of Fig. 3.

Figure 12 is an enlarged sectional view 25 through a basket handle and hanger carried thereby.

Figure 13 is a perspective view of the improved hanger.

This store which is indicated in general 30 by the numeral 1 is to be divided into the entrance chamber or lobby 2, the main show room and selling room 3 and rear room 4 which may be termed the store room or stock room. In order to divide the lobby

35 or portal 2 from the sales room 3, there has been provided a basket bin 5, a cashier's counter 6 having an outer railing 7 in which a door 8 will be provided and checking counter 9 where customers may check suit

40 cases, umbrellas and other articles and packages while purchasing. Within the show room or selling room 3, there has been provided a railing 10 which leads from the basket bin 5 and extends partially along the

45 cashier's counter 6 and thus provides an exit aisle through which the customers will pass when leaving the selling room. A turn stile 11 will be provided at the entrance

50 to the selling room and if desired a similar turn stile may be provided at the exit. The customers will usually pass out around the counter and between the counter and basket bin but at times it is desired to have them

55 pass out through a passageway which may be provided intermediate the length of the counter. There has therefore been provided

60 gates 44 and 45, drop boards 46 and 47 and a guard chain 48. If it is desired to have all of the customers pass around the counter

65 6, the gate 44 will be closed and the drop

board 46 supported in a raised position as shown in Fig. 4. The chain 48 will be put up and the gate 45 will be opened and the drop board 47 lowered so that clerks can pass from one end of the space behind the counter to the other. If it is desired to have the customers pass out through the passageway intermediate the length of the counter as well as around the counter and thus prevent crowding, the drop board 46 will be lowered, the gate 44 opened and the chain 48 removed thus providing the passage as shown in Fig. 3. The gate 45 will be closed and the drop board 47 raised to keep customers from going behind the counter 6. If desired, the gate 44 may be secured when swung half way open and thus form a barrier causing all of the customers to pass out through the intermediate passage of the counter. In order to support the drop boards 46 and 47 in a raised position, a supporting slide 49 will be provided for the free end of each of these drop boards. It will thus be seen that on busy days customers may be allowed to pass through the intermediate passage or around the end of the counter, on ordinary days they may be caused to all pass around the end of the counter, and on dull days they may be caused to pass through the intermediate 95 passage. A drop board 50 and gate 51 are provided so that a clerk can pass out into the selling room when necessary.

From an inspection of Fig. 2, it will be readily seen that there will be provided a 100 relatively large lobby at the front of the store building 1 and if desired this space may be made use of by demonstrators who wish to introduce to the public certain goods which may be purchased. It will also be noted from this view, that when a customer enters the store, the customer may check a suitcase or other article at the checking counter 9 and may then pass into the selling room through the entrance and while entering may very readily remove a basket 110 110 from the basket bin 5.

The shelving or other merchandise holders are arranged to provide two side sections indicated in general by the numeral 111 115 11 and a cross section which is indicated in general by the numeral 15. The side sections 11 of the shelving will be positioned against the side walls of the store building 1 and the cross section 15 will extend between the rear end portions of the side sections 11 and in addition to providing shelving, will also provide a partition dividing the selling room 3 from the stock room 4. This cross section 15 together with the side sections 11 will provide shelving having the general shape of a W. By having the cross section formed as shown in Fig. 2, the cashier who stands between the counter 6 and rail 7 and faces the rear of the selling 120 125 130 room will have a clear view of the entire

room may have an unobstructed view of the entire selling room and all of the customers may be watched so that a customer placing small bottles or other such articles in a 5 pocket instead of in the basket may be readily detected and petty stealing of this character prevented. This shelving will be formed in a plurality of units 16 formed as shown in Fig. 4 and will be placed one 10 against the other and will have their end walls 16^a contacting and straddled by clamps 17 carried by the brackets 18 which serve to support the basket track 19. The end 15 walls of the shelving units will have their outer edges faced by a facing strip 16^b and a strip of moulding 16^c will extend along the upper ends of the sections. The basket track 19 extends in front of the shelving and will be preferably formed of heavy 20 sheet metal stamped in the form of a trough so that the baskets may be suspended upon the outer edge portions of this trough. It will be noted that the basket track extends from the entrance to the cashier's counter 25 and therefore the empty baskets may be placed directly upon this track when entering the selling room and a filled basket may be easily removed from the track and placed upon the cashier's counter. It will 30 be further noted that since this basket track extends in a continuous course in front of all of the shelving, the customer may readily move the basket along the track in front of the shelving and may remove different 35 articles from the various shelves and place them in the basket. Since the purchaser in moving the basket along the basket track will pass all of the shelving, the attention of the customer will be attracted to all of the 40 goods on sale and many articles which might otherwise have been overlooked will be placed in the basket.

In connection with the cross section 15 which extends from the rear end of one of 45 the side sections 14 to the other and forms a partition dividing the selling room 3 from the stock room 4, it is desired to call attention to the fact that the forward end of the center extension will not be provided with shelves but will be provided with a door 20 which is hingedly mounted so that it may be swung open to permit of a clerk passing from the stock room into the selling room or from the selling room into the stock 50 room. The end portions of this cross section will however be formed of sections of shelving which, similar to the sections which form the rest of the shelving, are constructed similar to bookcase and are hingedly 55 mounted as shown at 21 and provided with rollers 22 so that these sections of the shelving may be swung open to permit of trucks being moved from one room to the other. It is of course obvious that in front of the 60 door 20 and end sections of the cross section

15 of the shelving, the portions 19' of the track must be movable so that they will not interfere with opening of the doors or prevent free passage from one room to another. These track sections 19' will therefore each 70 have one end hingedly mounted as shown at 19^a so that it may be swung up out of the way. The free end of the section 19' will rest upon a bracket 19^b which serves to prevent transverse movement of the hinged section as well as to support it. It should be further noted that the sections of shelving which form the side sections 14 are provided with shelves from their lower ends to their upper ends as shown in Figs. 1 and 4, where 80 as the sections of shelving which form the cross section 15 will have a somewhat different construction and will be provided with a forward wall 23 which will extend slightly above the counter 24. There are no 85 shelves above the counter but below the counter there will be provided shelves 25 upon which a clerk standing behind this counter may place surplus stock. Meats, fruits and vegetables which are easily contaminated or bruised by being handled are to be sold at these counters and in order to prevent customers from handling these articles, there will be provided guard frames 90 26 which extend rearwardly from the upper 95 end of the wall 23. These guards will be in the form of frames having glass mounted therein so that the customers can readily see the goods placed upon the counter.

Each of the baskets which are to carry 100 the articles purchased and are to be suspended upon the track 19 is provided with a handle 27 upon which will be mounted a carrier indicated in general by the numeral 105 28. Each of these carriers is formed as shown in Figs. 12 and 13 and is provided with a base plate 29 which will engage the upper face of the handle. This base plate has its end portions provided with openings 30 which are to register with openings 31 110 formed in a reinforcing plate 32 so that fasteners 33 may be passed through these plates and through the handle thus securing the carrier upon the handle and further reinforcing that portion of the handle upon 115 which the greatest strain will come. This carrier is provided with a vertically disposed standard 34 having at one side an eye 35 through which the finger may be passed when lifting the basket from the track. Upon the opposite side of the standard there has been provided an arm extension 36 having a depending end portion. A roller 37 is rotatably mounted between the standard 34 and the depending end portion 120 of this arm 36 and will engage the outer edge portion of the track 19 when the basket is suspended from the track as shown in Fig. 3. From an inspection of this figure, 125 it will be readily seen that the basket may 130

be readily placed upon the track and may also be easily removed from the track to permit of its being placed upon the cashier's counter or to permit of the basket being removed from the track while a purchaser is passing another purchaser who happens to be examining or removing articles which the first purchaser does not desire.

From the foregoing it will be understood
10 that the basket 13, with its handle 27, and

- 10 that the basket 13, with its handle 27, and hook over structure 28, constitutes a carrier adapted to be propelled along the track. The hook over structure, which includes the groove wheel 37 and a fixture 36, 34 journaling the same on substantially a horizontal axis, is mounted on a high point of the bail handle. The base 29 of this fixture comprises an integral strip portion which is offset from the remainder of the fixture and laid against one side of the bail, and the securing elements 33 which mount the fixture upon the bail also engage the plate or strip member 32 located on the opposite side of the bail.

25 It is desired to permit of signs advertising goods on sale to be displayed and in order to do so there will be provided a continuous signboard 38 which will extend along the top of the shelving. This signboard is constructed in units as shown in Fig. 6 and by reference to this figure, it will be seen that it will be provided with upper and lower strips 39 which extend longitudinally of the signboard and are connected by 30 vertically disposed cross strips 40. Spacing strips 41 are positioned between the strips 40 and a backing plate or card 42 thus providing pockets to receive the show cards 43. The end walls of the shelving units will be 45 cut back above the upper shelf as shown at 16° so that the signboard units can be put in place and secured against the end walls of the shelving units. The cards 43 upon which the advertising matter will be printed, will be put in the pockets of the signboard units as shown in Fig. 7 with their lower edges resting upon the top of the shelving as shown in Fig. 3. It will thus be seen that these cards can be easily removed and new ones put in place when desired.

When in use, the store will be constructed as described and shown in Figs. 1 and 2 and the customers will enter through the doors 52. Upon reaching the lobby 2, packages will be checked at the counter 9 and the purchasers will pass through the entrance and while doing so or just prior to passing through the entrance, the purchasers will remove baskets from the bin 5. These baskets will be hung upon the basket track and pushed along the track while articles are being placed in the baskets. If one customer wishes to pass another, the basket will be removed from the track and after the cus-

omer has passed around in front of the party it is desired to pass, the basket will be replaced upon the truck. When the cashier's counter is reached, the bill will be paid and the articles placed in a bag in which they are to be carried out of the store. The purchaser will then pass out through the exit and will drop the basket in the bin, or the baskets may be returned to the bin by a clerk.

I claim -

1. In a self serving store, a room having at its front portion a cashier's counter and associated entrance and exit passages, and at its rear portion a transverse partition ⁸⁰ which divides the room into a main store space and a storage space, said partition having a doorway closed by a door, a line of merchandise shelving extending around the main store space from the entrance to the ⁸⁵ exit passage, supporting brackets extending outwardly from the shelving, an elevated track rail fixed to said brackets, the portion of the track rail opposite the doorway having one end hinged and its free end removably supported on one of said brackets, said track rail extending in unbroken continuity from one end of the shelving to the other end, whereby a basket having on its handle a wheeled hanger to engage the track rail ⁹⁰ may be pushed from the entrance to the exit passage without being lifted from the track rail.

2. In a self-serving store, a room, shelving and a partition connecting the shelving and having a portion hingedly mounted to provide a passage and a closure door for said passage, a track strip extending in front of the shelving and partition, supporting brackets for said strip extending rearwardly therefrom and connected to the shelving and partition, certain of said brackets being positioned upon opposite sides of the passage and a portion of the track strip in front of the passage being hingedly mounted for vertical movement into and out of an operative position, and a bracket to one side of the passage extending to engage the free end of the movable track section and support the same in an operative position. 100 105 110 115 120

3. In a self serving store, a room having an inlet and an outlet, a cashier's counter adjacent one end, shelving extending from adjacent the inlet to a point adjacent said counter and having side sections and a cross section extending between the side sections and constituting a partition, a portion of the partition forming shelving being hingedly mounted for horizontal swinging movement to provide a passage and closure for the passage movable into and out of a closing position and having supporting rollers on its bottom to engage the floor, brackets secured to said shelving and extending out-

- wardly/therefrom, a track rail carried by said brackets and extending from one end of said shelving to the other and shaped for engagement by the roller of a basket hanger
- 5 to be suspended from and moved along said rail, a portion of the rail in front of the passage being hingedly mounted at one end for vertical swinging movement into and out of an operative position with respect to
- 10 the remainder of the rail, and a bracket for engaging the free end of the swinging rail section and supporting the swinging rail section in an operative position.
4. In a self-serving store, a room having
- 15 an inlet and an outlet, a continuous line of shelving extending from a point adjacent the inlet to a point adjacent the outlet and formed of a plurality of units having end walls and shelves carried thereby, the units
- 20 having their end walls abutting, an elevated track strip extending in front of said shelving for engagement by a roller of a basket hanger, and supporting brackets for said track strip including spaced fingers extending
- 25 along the sides of the abutting end walls of the shelf units and secured to mount the brackets and provide U-shaped clamps holding the units together.
5. In a store, a room having an entrance
- 30 and an exit, a counter extending across the exit, a guide extending about the counter to form a path leading to the exit, a guard rail between the counter and exit, partitions between the counter and guard rail each including a section movably mounted for movement into and out of an operative position, said guard rail being broken away between said partitions, a barrier for extending across the break in the rail between said
- 35 partitions movable into and out of an operative position, the counter having a section opposite said barrier movably mounted for movement into and out of an operative position, and a gate beneath the movable section of said counter movable outwardly to extend across the path between the counter and guide to provide a barrier for directing customers to the exit intermediate the length of the counter when the counter section and first mentioned barrier are in an inoperative position and further movable to a position against the wall of the counter to permit passage of customers about the end of the counter.
- 40 6. In a store, a room having an entrance and an exit, a counter extending across the
- exit, a guide extending about the counter to form a path leading to the exit, a guard rail between the counter and exit, partitions between the counter and guard rail, the guard rail and counter between the partitions being broken away to provide a passageway intermediate the length of the counter, a drop section for the counter hingedly mounted and movable into and out of position extending across the passageway, a gate for the passageway hingedly mounted beneath the drop section of said counter and opening into the path between the counter and guide to form a barrier and further
- 45 movable in an opening direction to leave the path unobstructed, and a barrier extensible across the break in the guard rail between said partitions.
7. In a self-service store, a salesroom having a portal, a plurality of merchandise holders within said salesroom, brackets on the sides of the merchandise holders, tracks mounted on the brackets and arranged so as to form a continuous course
- 50 with respect to said holders, and a carrier on said track adapted to be propelled along the same, while suspendedly carried thereby, said carrier being freely removable from said track and having means whereby it may
- 55 be suspendedly carried by the customer.
8. In a self-service store including display merchandise holders, the combination of a track extending in the vicinity of said holders, and a carrier detachably carried by the
- 60 track and adapted to be propelled along the same, said carrier being a container having a manually engageable suspension handle, said handle being a transverse bail, and said carrier also having a track-engaging hook-over structure, said structure including a grooved wheel and a fixture journailling the same on substantially a horizontal axis and mounted on a high point of the bail to extend above the same.
- 65 9. The track and carrier system defined in claim 8, wherein said fixture includes a base comprising an integral strip portion laid against one side of the bail, there being a strip member located on the opposite side of the bail, and securing elements for mounting the fixture on the bail, said elements also engaging said strip member.
- 100 In testimony whereof I have hereunto set my hand.

JOHN F. SMILEY.
